UNITED STATES PATENT OFFICE.

JAMES A. WILLIAMS, OF CINCINNATI, OHIO.

DESIGN FOR A GAS-LOG.

44,264.

Specification for Design. Patented June 24, 1913.

Application filed March 20, 1913. Serial No. 755,800. Term of patent 14 years.

To all whom it may concern:

Be it known that I, JAMES A. WILLIAMS, a citizen of Great Britain, residing at Cincinnati, in the county of Hamilton and State of Ohio, have invented a new, original, and ornamental Design for Gas-Logs, of which the following is a specification, reference being had to the accompanying drawing, forming part hereof.

In the drawings: Figure 1 is a perspective

view of a gas log showing my new design; Fig. 2 is an elevation of the same; Fig. 3 is a plan view of the same.

I claim:

The ornamental design for a gas log as shown.

JAMES A. WILLIAMS. [L.S.]
